COMBINED SLICER AND FORK

Earl S. Tupper, Smithfield, R. I.

Application May 23, 1955, Serial No. 36,148

Term of patent 14 years

(Cl. D44—29)

Fig. 1

Fig. 2

Fig. 4

Fig. 5

Fig. 6

Figure 1 is a top elevational view of a combined slicer and fork, embodying my new design;

Figure 2 is a front elevational view thereof;

Figure 3 is a bottom elevational view thereof;

Figure 4 is a sectional view thereof across the line 4—4 of Figure 3;

Figure 5 is a sectional view thereof across the line 5—5 of Figure 3; and

Figure 6 is a sectional view thereof across the line 6—6 of Figure 3.

I claim:

The ornamental design for a combined slicer and fork, substantially as shown.
